COMBINED CHAIR AND STEPLADDER

Andrew A. Harju, Ashtabula, Ohio

Application March 18, 1937, Serial No. 131,734

2 Claims. (Cl. 155—42)

This invention relates to a chair and more particularly to a construction whereby the chair may be converted into a step ladder, and it consists in the constructions, arrangements and combinations herein described and claimed.

It is an object of the invention to provide a chair which may be quickly and readily converted from a chair to a step ladder or vice versa, of few moving parts and which will be rigid and solid in either of its positions of adjustment.

It is a further object of the invention to provide a structure of the kind stated in which it is not necessary to dismantle any portion of the structure in order that the chair may be moved to form either the chair or ladder.

Additional objects, advantages and features of invention will be apparent from the following description considered in conjunction with the accompanying drawing, wherein

Figure 1 is a side elevation of the invention, shown in the form of a chair.

Figure 2 is a front view thereof.

Figure 3 is a side elevation of the invention, the parts having been moved to provide a step ladder.

Figure 4 is a rear elevation thereof.

There is illustrated, generally, a chair 10, a back structure 11 comprising a pair of upright members 12, connected by a plurality of transverse struts 13. As may be seen in Figure 1, the struts 13 are connected between the uprights at an angle so that when the device is converted into a step-ladder, the struts 13 will have a position with relation to the uprights so as to define the steps of the ladder. This will be more clearly apparent as the description proceeds.

A pair of front legs 14 are provided, connected intermediate their height by a flat rung 15. The rung 15 comprises rearwardly extending rungs 16, pivoted as at 17 to respective uprights 12.

A seat 18 is pivoted as at 19 to the upper ends of the front legs 14, and links 20 are pivotally connected at one end as at 21 to respective uprights 12, the other end of the links 20 being pivoted to the seat frame 22 as at 23. The frame 22 is preferably undercut as at 24 to accommodate the links 20, and in the position of the parts when employed as a chair, the links bear upon the under portion of the slots, thereby affording rigidity to the chair. The seat 18 may be suitably reinforced by members 25 and 26 suitably secured to the under face of the seat.

Each upright 12 has a laterally extended lug 28 positioned adjacent the upper ends of the uprights, and the frame members 22 have provided

in their free ends a notch 28, the notches co-operating with the lugs in a manner presently to be described.

With the device set up as a chair as shown in Figure 1, and it is desired to convert the device into a ladder, it is only necessary to hold the back of the chair with one hand, and with the other hand the seat is lifted, the seat pivoting on the front legs 14, by virtue of pivots 19. The seat 18 is raised until the notches 28 register with respective lugs 27 so as to seat therein. In such position of the parts, the uprights 12 will be inclined in a direction toward the front legs, and the struts 13 thus form the steps of the ladder. The links 20 serve to prevent collapse of the device as well as afford rigidity.

While I have shown and described a preferred embodiment of the invention, this is by way of illustration only and I consider as my own all such variations in structure as fairly fall within the scope of the appended claims.

I claim:

1. A combined chair and step-ladder comprising upright members including a plurality of spaced strut members, front leg members, the front leg members having a rearwardly extended rung member pivotally connected to respective upright members, a seat member pivotally connected to respective front leg members, a link connected between each upright and a forward portion of the seat, a laterally extended lug on each upright and the free end of the seat member having notches for registry with respective lugs of the uprights in one position of the parts.

2. A combined chair and step-ladder comprising upright members having step members connected therebetween, a pair of front leg members, the front legs having a rung member extended rearwardly therefrom and pivotally connected to respective upright members, a seat member including side frame members, said frame members being pivotally connected to the upper ends of the front leg members, each of the frame members having a slot formed upon the under face thereof, a link member pivoted at one end to respective uprights at a point slightly below the pivot of the front legs, the other end of the links being pivoted to the seat, the links normally occupying a position within and abutting the base of the slot, a laterally extended lug on each upright adjacent the upper ends thereof, and the free ends of the frame members having a notch for reception of respective lugs, in one position of the parts.
